UNITED STATES PATENT OFFICE.

ALEXANDER YOUDELMAN, OF NEW YORK, N. Y.

STOPPER.

1,187,221.

Specification of Letters Patent. Patented June 13, 1916.

Application filed August 19, 1915. Serial No. 46,328.

To all whom it may concern:

Be it known that I, ALEXANDER YOUDELMAN, a citizen of the United States, and a resident of the city of New York, borough 5 of Manhattan, in the county and State of New York, have invented a new and Improved Stopper, of which the following is a full, clear, and exact description.

My invention relates to stoppers, and has 10 reference more particularly to rubber or rubber-composition stoppers used for sinks, tubs, washbowls, etc.

The object of the invention is to provide a simple, strong and inexpensive stopper 15 which will not leak at the connection of the manipulating means with the body of the plug.

With the above and other objects in view, the nature of which will more fully appear 20 as the description proceeds, the invention consists in the novel construction, combination and arrangement of parts as herein fully described, illustrated and claimed.

In the accompanying drawings, forming 25 part of the application, similar characters of reference indicate corresponding parts in all the views.

Figure 1 is a perspective view of a preferred form of my invention; Fig. 2 is a vertical section therethrough; Fig. 3 is a section through a modified form of the anchoring disk; and Fig. 4 is a plan view of a further modified form of the anchoring member.

35 Referring to the drawings, 5 represents a plug which is formed of flexible and resilient material, such as rubber or rubber composition. The lower part of the lateral surface of the plug is preferably cone shape to facilitate the engagement of the plug with the opening it is supposed to close. The plug 5 has a circular recess 6 in the top thereof and the bottom of which an under-cut groove 7 is formed in the wall of the recess. Engaging tightly the under-cut groove 7 of the plug is a disk 8 which rests on the bottom of the recess. The disk has preferably a raised portion 9 formed from the body of the disk and engaged by a ring 10, which 45 forms the manipulating means for the plug. The disk 8 is anchored to the plug 5 by the

gripping of the disk by the body of the plug, due to the resiliency thereof.

The body of the plug 5 having no through opening in the body for the connection of the 55 manipulating means for the plug, there is no chance for a leak through the connection. In the plugs at present in use, the manipulating means for the plug pass through the body of the plug, being riveted at the lower 60 end thereof. After a certain time of wear liquid finds its way through the opening engaged by the manipulating means.

In Fig. 3 a modified structure of the anchoring disk is shown. In this structure 65 the margin 11 of the disk 7' is raised to increase the gripping action of the plug body on to the disk. The disk 7'', shown in Fig. 4, has a bent toothed edge 12 which can also be used to prevent the tendency of the anchoring disk to turn within the body of the 70 plug.

I claim:

1. In a stopper, a plug of rubber or rubber composition having a cylindrical upper 75 portion and a cone-shaped lower portion, the said plug having a circular recess in its top, a disk member fitting in the bottom of said recess and having a toothed marginal edge, the said edge being gripped by the 80 body of the plug, and a manipulating member for the plug engaging said disk member.

2. In a stopper, a plug of rubber or rubber composition having a cylindrical upper portion, and a cone-shaped lower portion, 85 the said plug having a circular recess in its top and an undercut groove in the bottom of the recess formed in the wall thereof, a disk having a toothed edge fitting in the said undercut groove and gripped by the 90 body of the plug to prevent the disk from turning within the said body of the plug, the said disk having a raised portion and a ring engaging the raised portion of the disk.

In testimony whereof I have signed my 95 name to this specification in the presence of two subscribing witnesses.

ALEXANDER YOUDELMAN.
